UNITED STATES PATENT OFFICE

RALPH L. BROWN, OF NEWARK, NEW JERSEY, ASSIGNOR TO BRANDES LABORATORIES, INC., OF NEWARK, NEW JERSEY, A CORPORATION OF NEW JERSEY

SOUND REPRODUCER

Application filed March 4, 1927. Serial No. 172,767.

My invention relates broadly to sound reproducers and more particularly to a conical shaped sound reproducing diaphragm having means for improving the sound reproducing qualities of the diaphragm.

One of the objects of my invention is to provide a sound reproducing diaphragm having means for damping the excess vibration of the diaphragm for preventing weaving of the edge of the diaphragm and eliminating undesirable rattling and inherent diaphragm noises.

Another object of my invention is to provide a damper for a cone shaped sound reproducing diaphragm for the prevention of undesired noises arising from distortion of the shape of the diaphragm which normally tend to interfere with the sound reproducing qualities of the cone.

Another object of my invention is to provide a construction of damper in the form of a loose woven fabric member arranged to conform with the shape of a conical shaped sound reproducing diaphragm for preventing excess vibration thereof.

Another object of my invention is to provide a sheet-like member forming a damper for a cone shaped sound reproducing diaphragm where the sheet-like member closely conforms to the base of the diaphragm for eliminating blasting of the edge of the diaphragm and thereby improving the sound reproducing qualities of a diaphragm which is supported wholly at its apex.

Other and further objects of my invention reside in the construction of a damper for a conical shaped sound reproducing diaphragm as more fully described in the specification hereinafter following by reference to the accompanying drawings in which:

Figure 1 is a side elevation of a cone shaped sound reproducing diaphragm embodying the principles of my invention; Fig. 2 is a plan view of the conical shaped sound reproducing diaphragm of my invention showing

the damper arranged in position with respect thereto; Fig. 3 is an elevational view looking at the back of the cone shaped diaphragm and showing the damper of my invention in position with respect to the diaphragm; Fig. 4 is a perspective view of a cone shaped sound reproducing diaphragm showing the damper of my invention in position; Fig. 5 is a plain view showing the damper sheet cut to shape and ready for application to the cone shaped sound reproducing diaphragm; Fig. 6 is a cross-sectional view taken through a fragmentary part of a cone shaped sound reproducing diaphragm and illustrating the damper set in position with respect to the diaphragm; Fig. 7 is a rear plan view illustrating a modified form of damper applied to a cone shaped sound reproducing diaphragm in accordance with the principles of my invention; and Fig. 8 is a cross-sectional view taken through the modified construction of the damper illustrated in Fig. 7.

My invention relates to that class of sound reproducing diaphragms which are supported from the apex and have a free peripheral edge. Sound vibrations are applied to the apex of the conical shaped sound reproducing diaphragm and the entire surface set into vibration for the reproduction of sound. Under conditions of large amplitude of the impressed sound at the apex of the cone the peripheral edge of the cone is often subjected to such excessive vibration that the edge tends to weave and blast, setting up undesired rattling noises which seriously interfere with the sound reproduction. It is for the purpose of improving the quality of sound reproduction from conical shaped diaphragms that I have applied the damper illustrated in the accompanying drawings to the surface of the cone preventing the undesired weaving and blasting and thereby eliminating rattling noises. The construction of damper illustrated in the drawings has been found to be

extremely practical and successful in its operation.

Referring to the drawings in more detail reference character 1 illustrates a base support which carries a standard 2 on which is mounted an electromagnetic driver 3 having an armature member 4 from which extends a connecting link 5 which supports the conical shaped sound reproducing diaphragm 6 10 from the apex thereof. The conical shaped sound reproducing diaphragm 6 is substantially free at its peripheral edge 7, but for the purpose of preventing blasting of the edge I provide a flexible connecting member 8 around the peripheral edge as illustrated in Fig. 6. A frame member 9 may be provided to which the flexible strip 8 is connected. A vertically extending member 10 is connected with the base 1 to which the frame 9 is connected. The damping means of my invention consist of a sheet of loose woven fabric 11 having a soft nap and formed to fit over the outside of the cone 6 in such a manner that the nap of the fabric 15 rests readily upon the outside wall of the cone. The damper 11 is attached to the cone at its outer periphery 12 and extends up the slant height of the cone to such a distance as is required to damp the excess vibrations. 20 This distance depends upon the style and size of the cone being used but is normally substantially more than half the slant height. Finally, I find that by laying the flannel over two-thirds of the area of the cone that the 25 excess vibrations are sufficiently damped to prevent blasting of the edge of the cone. The surface of the cone normally tends to form loops and nodes, and it is for the purpose of damping the amplitude of these waves that 30 the flannel member 11 is applied to the body of the cone.

In Figs. 7 and 8 I have shown a modified arrangement of the damper and its connection to the peripheral edge of the cone where 45 the separate damping strip 8 is not employed, but in lieu thereof the loose woven fabric sheet 11 extends beyond the peripheral edge 7 of the cone body 6 and is itself flexibly connected to the frame 9. The damper 11 there- 50 by serves to control the blasting of the raw edge 7 of the cone as well as to reduce the amplitude of motion through the body of the cone. The fabric sheet 14 in Fig. 7 is shown as secured throughout an annular portion 55 15 in the peripheral edge 7 of the cone, while the loose fabric extends both over the surface of the cone 6 and outwardly through a flexible portion 16 to the frame 9. It is not the purpose of the flexible member 14 to 60 provide a support for the cone but merely to damp the vibration of the cone, as it will be apparent that the cone is supported wholly from its apex.

The system of damping cones in accordance with my invention has been found to be

extremely practical and efficient in its operation, and while I have described preferred embodiments of my invention, I desire that it be understood that modifications may be made and that no limitations upon my invention are intended other than are imposed by the scope of the appended claims.

What I claim as new and desire to secure by Letters Patent of the United States is as follows:

1. A sound reproducer comprising a cone shaped diaphragm, means for imparting sound vibrations to said diaphragm and a ring of flexible fabric constituting a sound vibration damper extending over the surface 80 of said cone shaped diaphragm adjacent the peripheral portion thereof and remote from the center for limiting the vibration of the peripheral portion of said cone.

2. A sound reproducer comprising a sound reproducing diaphragm, means for imparting sound vibrations to said diaphragm and a belt of woven fabric constituting a sound vibration damper extending over substantially one-half the surface of said sound reproducing diaphragm remote from the central portion thereof.

3. A sound reproducer comprising a sound reproducing diaphragm, means for imparting sound vibrations to said diaphragm and a strip of flexible fabric constituting a sound vibration damper extending over a portion of the area of said diaphragm remote from the center of the diaphragm, the central area of said diaphragm operating independently 100 of said damper for developing vibrations controllable adjacent the periphery of said diaphragm by said damper.

4. A sound reproducer comprising a cone shaped diaphragm, means for imparting sound vibration to said diaphragm and a sound vibration damper extending over the surface of said cone shaped diaphragm adjacent the periphery thereof and remote from the apex of the diaphragm, said damper comprising a ring of flexible cloth closely adhering to the surface of said diaphragm adjacent the periphery of the diaphragm.

5. A sound reproducer comprising a cone shaped diaphragm, means for imparting sound vibration to said diaphragm and a sound vibration damper extending over the surface of said cone shaped diaphragm, said damper comprising a ring of loose woven cloth closely adhering to the surface of said diaphragm in a position remote from the center of said diaphragm.

6. A sound reproducer comprising a conical shaped sound reproducing diaphragm, means for imparting sound vibrations to said diaphragm and a ring of cloth encircling the base of said sound reproducing diaphragm and extending up the surface of the cone substantially more than one-half the slant height thereof and remote from the apex of 130

the cone for damping the vibration of the sound reproducing diaphragm.

7. A sound reproducer comprising a conical shaped sound reproducing diaphragm, means for imparting sound vibrations to said diaphragm, a damper secured to the peripheral edge of said sound reproducing diaphragm and extending loosely over an annular area comprising substantially more than half the surface area of said sound reproducing diaphragm for preventing excessive vibration of said diaphragm.

In testimony whereof I affix my signature
RALPH L. BROWN.
